UNITED STATES PATENT OFFICE.

WILLIAM ZITELLA, OF ADAMSTON, WEST VIRGINIA.

RAIL-JOINT.

1,383,050.

Specification of Letters Patent. Patented June 28, 1921.

Application filed May 3, 1921. Serial No. 466,436.

To all whom it may concern:

Be it known that I, WILLIAM ZITELLA, a citizen of the United States, residing at Adamston, in the county of Harrison and State of West Virginia, have invented a new and useful Rail-Joint, of which the following is a specification.

This invention relates to rail joints, one of its objects being to provide rails having their ends so shaped that one end of one rail can be forced downwardly into the other end of the opposed rail, there being coöperating means upon the interfitting portions of the rails whereby they are automatically locked together when placed in proper relation to each other and cannot be separated without cutting rivets or similar holding devices used in connection with the rails.

Another object is to provide a rail having a forked end in which are located blocks carrying holding dogs, these blocks being held in position by rivets or the like and being so arranged as to be straddled by the inserted end portion of another rail and which inserted portion will engage the dogs and be held in position thereby.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown:

40 In said drawings—

Figure 1 is a side elevation of portions of two rails and showing the interfitting ends thereof.

Fig. 2 is a section line 2—2, Fig. 1.

45 Fig. 3 is a section on line 3—3, Fig. 2.

Fig. 4 is a section on line 4—4, Fig. 3.

Fig. 5 is a section on line 5—5, Fig. 3.

Fig. 6 is a view similar to Fig. 3 but showing a slightly modified construction.

50 Referring to the figures by characters of reference 1 designates a portion of a rail the web of which is thickened at one end as indicated at 2 and provided with a longitudinal slot 3, the head of the rail being cut away above this slot so as to provide a shoulder or abutment 4 beyond which the forked or slot-

ted web extends. Arranged within the slot 3 at desired points are blocks 5 each of which is preferably held in place by a series of rivets 6 extending transversely through the blocks and through the spaced sides of the web as shown particularly in Fig. 2. These blocks extend from the top to the bottom of the slot and each of them is provided, in its opposed edges with recesses 7. A dog 8 is pivotally mounted at its upper end within each recess as shown at 9 and a spring 10 is interposed between the lower portion of each dog and the back wall of the recess, there being a socket 11 within the block in which the inner end portion of the spring is seated. These springs serve to hold the lower ends of the dogs normally pressed outwardly as shown in Fig. 3.

Another rail 12 adapted to be joined to the rail 1 has its base flanges 13 cut away along the web at the end portion thereof, the thickness of the web being substantially equal to the width of the slot 3. This web, which has been shown at 14, has cut away portions 15 extending thereinto from its lower edge and which are spaced apart and so proportioned that when the web 14 is pushed downwardly into the slot 3 the blocks 5 will be received within said cut away portions and the head of the rail 12 will rest upon the spaced portions of the web 2 and will approximately abut against the shoulder 4. The walls of each of the cut away portions 15 are provided with notches 16 so that when the web 14 is pressed downwardly into the slot 3 the dogs 8 will first be thrust back into the recesses 7 and will subsequently spring out into the notches 16, thus holding the two rails secured together firmly so that they cannot be removed under ordinary circumstances. As a matter of fact the only way in which the rails can be removed is by cutting the heads of the rivets 6 and forcing these rivets out of the blocks 5 after which the web 14 together with the blocks 5 can be pulled longitudinally from between the spaced side portions of the web 2. In order to reassemble the parts it is first necessary to insert the blocks 5 in their positions and fasten them by means of rivets after which the rails can be reassembled as heretofore explained.

55 Lateral enlargements 17 can be provided upon the sides of the rail 12 to provide shoulders 18 adjacent to which the spaced sides of the web 2 can abut as shown. It

is to be understood of course that the base flanges of the rail 1 are extended along the slotted portions of the web 2 so as to come against or in close proximity to the base flanges 13 of the rail 12 when the two rails are assembled.

In Fig. 6 a slightly modified form of joint has been illustrated. In this structure the blocks 19 arranged in the slot in one end of the rails are preferably tapered as shown and interposed between the blocks is a supplemental block 20. The blocks 19 are provided with dogs 21 similar to those heretofore described and the tongue 22 which is insertible downwardly into the slot is provided with cut away portions 23 designed to receive the blocks 19 and another cut away portion 24 designed to receive the block 20. Only the blocks 19 are provided with dogs, the block 20 merely serving as a centering and supporting means. In all other respects this modified structure is similar to that heretofore described.

What is claimed is:—

1. In a rail joint the combination with a rail having a longitudinally slotted web, the head of the rail being removed above said slotted web, of a block secured within the slot in the web, resiliently held dogs upon the block, a rail having a web insertible downwardly into said slot, said web being provided with a space for the reception of the block, there being means upon the walls of said space for engagement by the dogs.

2. In a rail joint the combination with a rail having a longitudinally slotted web, the head of the rail being removed above said slotted portion of the web, of a block within the slot, means extending transversely through the web and block for holding the block in position, a rail having a web insertible downwardly into the slot, there being a space in said insertible web for the reception of the block, and co-operating means upon the block and the walls of said space for automatically securing the webs together. 40 45

3. In a rail joint the combination with a rail having a longitudinally slotted web, the head of the rail being removed above the slot, of spaced blocks within the slotted web, means extending transversely through the web and blocks for holding the blocks in position, spring pressed dogs mounted in opposite portions of each block, another rail having a web insertible downwardly into the slot, said insertible web having spaces for the reception of the blocks, there being notches within the walls of said 60 spaces for the reception of the dogs thereby to hold the webs together when inserted one into the other. 50 55

In testimony that I claim the foregoing as my own, I have hereto affixed my signature in the presence of two witnesses. 65

WILLIAM ZITELLA.
